UNITED STATES PATENT OFFICE

163,233

COMBINED DESK LAMP AND CLOCK

Oliver H. Williams, Elkhart, Ind., assignor to Industrial Lamp Corporation, Elkhart, Ind., a corporation of Illinois

Application May 25, 1950, Serial No. 10,190

Term of patent 14 years

(Cl. D48—20)

To all whom it may concern:

Be it known that I, Oliver H. Williams, a citizen of the United States, residing at Elkhart, in the county of Elkhart and State of Indiana, have invented a new, original, and ornamental Design for Combined Desk Lamp and Clock, of which the following is a specification, reference being had to the accompanying drawing, constituting a part hereof.

Fig. 1 is a front perspective view of a combined desk lamp and clock showing my new design;

Fig. 2 is a top plan view thereof; and

Fig. 3 is a side elevational view to a reduced scale.

I claim:

The ornamental design for a combined desk lamp and clock, substantially as shown.

OLIVER H. WILLIAMS.
